[57] CLAIM

The ornamental design for a bottle or the like, as shown and described.

DESCRIPTION

FIG. 1 is a perspective view of a bottle or the like showing our new design;

FIG. 2 is a rear elevational view thereof;

FIG. 3 is a side elevational view thereof, with the opposite side being identical except for the thread orientation;

FIG. 4 is a front elevational view thereof;

FIG. 5 is a top plan view thereof; and

FIG. 6 is a bottom plan view thereof.
